(57) **CLAIM**

I claim the ornamental design of a lighting fixture, as shown and described.

DESCRIPTION

FIG. 1 illustrates a top perspective view of a lighting fixture. FIG. 2 illustrates a bottom perspective view of the lighting fixture.

FIG. 3 illustrates a first side view of the lighting fixture. FIG. 4 illustrates a second side view of the lighting fixture.

FIG. 5 illustrates a first end view of the lighting fixture.

FIG. 6 illustrates a second end view of the lighting fixture.

FIG. 7 illustrates a top view of the lighting fixture.

FIG. 8 illustrates a bottom view of the lighting fixture.

FIG. 9 illustrates a cross-section of the lighting fixture taken along line 9-9 of FIG. 7.

FIG. 10 illustrates an enlargement of a portion of FIG. 1 identified with numeral 10; and,

FIG. 11 illustrates an enlargement of a portion of FIG. 2 identified with numeral 11.

The broken lines in the Figures are for illustrative purposes only and form no part of the claimed design. The shade lines in the Figures show contour or the flatness of a surface, and not surface ornamentation.
